Primary Examiner — George D. Kirschbaum*Assistant Examiner* — Joseph J Kukella(74) *Attorney, Agent, or Firm* — Greenblum & Bernstein, P.L.C.(57) **CLAIM**

The ornamental design for plush figure, as shown and described.

DESCRIPTION

The patent or application file contains at least one drawing executed in color. Copies of this patent or patent application publication with color drawing(s) will be provided by the Office upon request and payment of the necessary fee.

31. Plush figure

31.1 is a front side perspective view of a plush figure in accordance with another embodiment of the invention;

31.2 is a right side perspective view of 31.1;

32.1 is a right side perspective view of a plush figure in accordance with another embodiment of the invention; and

32.2 is a front side perspective view of 32.1.

Any surfaces of the design not shown, including interior surfaces and any surfaces shown in broken lines, form no part of the claimed invention.
